UNITED STATES PATENT OFFICE.

HENRY KLEIN, OF NEW YORK, N. Y.

INTERIOR PARTITION.

1,253,499.

Specification of Letters Patent. Patented Jan. 15, 1918.

Application filed November 13, 1912. Serial No. 731,218.

To all whom it may concern:

Be it known that I, HENRY KLEIN, now a citizen of the United States of America, residing at New York city, in the county of 5 New York and State of New York, have invented certain new and useful Improvements in Interior Partitions, of which the following is a specification.

This invention relates to certain improvements in and relating to interior partitions, and the like, for buildings, and the objects and nature of the invention will be readily understood by those skilled in the art in the light of the following explanation of the accompanying drawings illustrating what I now believe to be the preferred embodiment from among other formations, arrangements and constructions within the spirit and scope of my invention.

An object of the invention is to provide certain improvements in and relating to the office partition, or the like, illustrated by my Patent No. 956,642, dated May 3, 1910, and particularly for the provision of constructions and arrangements whereby standardized units can be made and completely finished in the factory, and kept in stock, for shipment knocked down, and so that such units can be readily fitted together, set up, and assembled to form complete finished-surface partitions of various heights and lengths without necessitating the employment of skilled or expert labor to touch up, varnish or otherwise finish the surfaces of 35 the partition after completion thereof, and without requiring high priced expert assistance in setting up and assembling such units to form the complete located partition.

A further object of the invention is to provide certain improvements in details of construction and in arrangements of parts, to reduce the cost of production, and to attain certain advantages in assembled removable office partitions and the like.

The invention consists in certain novel features in construction and in combinations and arrangements as more fully and particularly set forth hereinafter.

Referring to the accompanying drawings;

Figure 1, shows part of a partition constructed in accordance with my invention.

Fig. 2, is a side elevation, partially in ver-

tical section taken longitudinally of the partition.

Fig. 3, is a vertical section on the line 55 3—3, Fig. 1.

Fig. 4, is a detail perspective of a lower or main post or pilaster, and of a main or lower filling or panel unit or section, shown 60 separated from the post and partially broken away.

Fig. 5, is a section on the line 5—5, Fig. 1.

Fig. 6, is a section on the line 6—6, Fig. 1.

Fig. 7, is a section on the line 7—7, Fig. 1. 65

Fig. 8, is a perspective view of a detail.

Fig. 9, is a detail view illustrating co-operating interlocking formation of the side edges of the post extensions and the end edges of the horizontal rails of the partition 70 extension top.

The main, lower or body part of the partition is made up of a series of similar posts or pilasters *a*, and a number of similar filling or panel sections or frames *b*, closing the spaces 75 between the posts and removably fitted thereto. These posts and sections are preferably mounted on a base or floor board or strip 1. This strip consists of a flat board resting on and if desired secured to the floor 80 and having a central depressed groove 2, throughout the length of its top face. The lower edges of the posts and sections rest on the top faces of the strip at both sides of the groove. The lower ends of the posts can, if 85 so desired, be formed with central depending projections or tongues 3, to enter said grooves; and the lower edges of the sections can also be formed with central depending tongues or projections 4, to enter said 90 grooves. The lower ends of the posts are fixed to the floor strip by angle or elbow irons or brackets 5, having their horizontal arms fixed to the strip and arranged in the groove thereof, and having their vertical 95 arms fixed to the posts and engaging the central portions of the vertical side edges thereof so that these securing brackets will be concealed by the sections when fitted to the posts and floor strip.

100 The posts and sections are preferably of the same height and horizontal coupling irons 6, are removably secured on the top edges of the posts and sections. Each coupling iron is secured to and extends across 105 the top edge of a post and onto the top edges

of the two sections fitting the post and is removably secured to said sections by screws or the like.

The sections and posts are also secured together at their upper ends by crown moldings 7, to stiffen and strengthen the partition and to provide the desired finish along the top edge of the body or lower portion of the partition.

10 These crown moldings are provided in long lengths so as to be continuous across as many sections and posts as possible whereby unbroken or continuous portions of said moldings will bridge the joints between the 15 posts and sections.

These moldings are preferably arranged along both sides of the partition and are applied thereto after the posts and sections are set up and fitted together. The crown 20 moldings fit the side faces of the upper ends of the posts and sections and are removably secured thereto by horizontal screws 8, extending inwardly through the molding and into the posts and sections. I preferably employ flat head screws and after the 25 moldings have been secured by said screws, I cover and conceal the screw heads by flat strips 9, arranged longitudinally of the moldings and removably secured thereto.

30 The upper extremities of the posts and sections are preferably of the same transverse thickness so that their opposite side faces will be flush to receive the straight crown moldings that connect and secure the 35 upper ends of the sections and posts together.

The posts are longitudinally hollow at their upper ends for the reception of post or pilaster extensions 10, where the partition 40 is to be extended to the ceiling. Each post is internally formed to longitudinally receive an extension 10, composed of a single stiff bar or strip freely slideable longitudinally in the post for adjustment to the ceiling. These extensions when moved up to the desired height can be secured to the 45 posts by angle brackets 11, fixed on the top end faces of the posts and having vertical arms extending up at the side faces of the 50 extensions and receiving removable horizontal screws entering the extensions and supporting the same as described in my Patent No. 956,642.

The upper extremities of the post extensions 55 10, in the example illustrated, fit into and enter a grooved ceiling strip 12, arranged longitudinally of the partition and along the ceiling. This strip 12, can be lightly and removably secured to the ceiling 60 to hold the same in place until the post extensions are fitted thereto, as these extensions will support said strip.

The spaces between the post extensions are filled in by suitable means, such as frames, 65 or panels composed of glass panes or sec-

tions 13, fitted to the opposite vertical edges of the post extensions and to the longitudinal edges of horizontal upper and lower rails 14, 15, fitted to and between the post extensions.

The lower rails 15, rest longitudinally on the top edges of the main partition sections between the posts, while the upper rails 14, are held and secured by upper crown moldings 16, traversing the opposite side faces 75 of the post extensions and removably secured thereto by screws or other means, and extending along the longitudinal side faces of the rails 14, and removably secured thereto by screws, or other means.

If spaces occur between the ceiling strip 12, and the upper crown moldings 16, such spaces can be filled in by suitable material; I show removably-secured light boards 17, such as beaver boards, or the like, fitting the 85 opposite edges of the ceiling strip and at their lower edges resting between the two opposite crown moldings.

Each main post is composed of a pair of longitudinal parallel side pieces 18, and 90 means suitably and rigidly fixing said pieces the required distance apart.

In the particular example illustrated, a spacing block 19, is secured between the lower end portions of said pieces. Above 95 the block 19, the pieces 18, are rigidly held in the required relative positions by stiff strong metal fasteners 20. The opposite edges of the pieces 18, are longitudinally rabbeted to form the longitudinal depressed 100 flat seats or shoulders 21, throughout the lengths of the pieces. When the two pieces 18, are secured to form the post, their rabbeted edges coincide to provide the opposite longitudinal edges of the posts with comparatively wide grooves extending throughout the lengths thereof, to receive the vertical edges of the sections b, of the partition. The floors of these grooves are formed by the shoulders 21, and the metal fasteners 20, 110 (except at the lower end of the post where the block 19, intervenes) extend transversely between shoulders 21. Each fastener 20, consists of a flat length of strong sheet metal at its end portions having down 115 turned spurs or prongs. These fasteners are arranged at intervals along and transversely of the opposite edges of the post. The fasteners are uniform in length and traverse the open space between the pieces 120 18, and their end portions fit transversely on the shoulders 21, and the prongs thereof are forced thereinto to secure and rigidly fasten said pieces. These fasteners accurately maintain the pieces in proper relation and the desired distance apart and form the edge walls of the longitudinal bore of the post in which the extension bar or post 125 10, is longitudinally adjustable and confined.

The posts can be quickly, accurately and 130

economically constructed through the employment of these metal fasteners, and I produce a post of superior qualities; and I also avoid expensive cabinet and gluing operations such as are necessary where hollow posts are built up of four longitudinal strips, as will be readily understood by those skilled in the art.

These posts can be made up and completely finished, and kept in stock, as said posts are similar and interchangeable and each constitutes a standardized unit, and the same is true of the extension posts or pilasters 10. Each main post unit includes 15 an extension 10.

The panel or filling sections b, are also made up completely finished and kept in stock, as said parts are similar and interchangeable and each constitutes a standardized unit, to fit any one of the posts.

Each section b, can comprise a desirable number of panels and frames therefor. In the example illustrated, I show each section embodying two panel frames 22, one containing 25 a wood or other opaque panel 23, and the other a glass or other transparent panel or pane 24. These panel frames 22, can be similar in size made from molding of the same dimensions. The two panel frames are 30 separated by and secured in a chair-rail or midrail-forming molding 25, grooved at its lower and upper edges to receive the horizontal top rail of the lower panel frame and the bottom rail of the upper panel frame. 35 The mid-rail or chair-rail 25, forms a transverse strengthening and stiffening rail across the intermediate or central portion of the panel or filling section b.

The bottom rail of the lower panel frame 40 22, is secured to and between the bottom opposite-side finishing or wash board moldings or boards 26. These boards 26, are secured together and constitute the lower end of the panel section or unit.

45 The top rail of the upper panel frame 22, is fitted in and secured to the stiff heavy top rail or bar 27, of the panel section or unit.

The crown moldings 7, are secured to this top rail 27, after the several units have been 50 assembled to form the partition, and this top rail also forms the upper end of the panel section or unit of the desired transverse thickness to approximately equal the transverse thickness of the upper ends of the 55 posts.

I am enabled to cut rails and moldings 26, 25 and 27, to exact lengths and thus successfully assemble the parts of and build individually complete interchangeable panel 60 sections in the factory so that they can be kept ahead in stock, by utilizing a pair of similar stiles or strips 28, to form the opposite longitudinal or vertical edge portions of each panel section. These stiles constitute the essential supporting elements of 65

the panel section and extend throughout the length thereof except for the top rail 27 which preferably traverses the top of the panel section. An individually complete panel section for use in the combinations of 70 elements constituting my improved partition embodies suitable means rigidly connecting said two stiles and filling in the space between the same, although in the particular example illustrated the space between these stiles is 75 occupied by the various rails and panels hereinbefore mentioned, and the stiles are centrally and longitudinally grooved throughout the lengths of their inner or adjoining edges to receive and center said filling elements and maintain them against lateral displacement from the panel section.

These central grooves in the stiles form the inner edge of each stile with a pair of parallel longitudinal shoulders, separated 35 by the groove, against which the end edges of the rails 25 and 26 tightly abut and to which they are secured, while between the various rails said shoulders are exposed, as the thickness of the panels and their frames 90 are less than the thickness of the stiles.

The stiles are formed with parallel or flat front and rear vertical side faces to form portions of the exposed side faces of the panel section in a completed partition. 95

These stiles of the individually-complete panel sections or units are of a thickness to enter and snugly fit the opposite longitudinal sockets of the individually-complete post units when assembling the parts of a 100 partition, but the width of the exposed side faces of said stiles is considerably greater than the depth of said sockets, so that in the completed partition considerable portions of the widths of said side faces are located 105 outside of said sockets to provide a desirable finish and conceal the joints between the panel and post units even though the units (where composed of wood) shrink unequally or the post units become somewhat warped. 110 The stiles of the sections will allow for considerable unevenness between the post and section units before exposing a crack between a post unit and a panel section unit.

The various completed units can be completely finished and surfaced (varnished, shellacked, or oiled and rubbed) before being shipped, inasmuch as the units can be assembled and put up to form the completed partition without the necessity of marring 115 or injuring the surface thereof and without leaving unfinished joints or surfaces.

By practising my invention, the partition can be set up by almost any man who knows how to handle tools, and after completion, 120 does not require the services of an expert surface finisher. A great saving in expense is effected by so completing the units in the shop, that the partition can be shipped or forwarded knocked down and then assem- 125 130

bled and set up, without requiring an expert from the shop or factory for pointing up and surfacing. I am also thus enabled to ship knock down partitions to distant points where finishers could be secured only at prohibitory expense.

10 The post extensions 10, are finished up complete in the shop and throughout their longitudinal edges are formed with central longitudinal beads or ribs 30, including removable sections for securing the panes of glass 13, as will be readily understood by those skilled in the art.

15 The upper and lower horizontal rails 14, 15, of the top extension of the partition are cut to exact lengths and finished in the shop. These upper and lower rails are preferably similar and interchangeable and their end edges are grooved in the shop, see 31, to fit 20 and receive the beaded edges of the post extensions 10. One longitudinal edge of each rail 14, 15, is formed to receive a pane of glass and is provided with removable beads for securing the glass.

25 The longitudinal edges of the post extensions 10, are formed with longitudinal grooves 33, on both sides of the ribs 30, and the end edges of each rail 14, 15, are formed with a pair of tongues 34, to enter said 30 grooves 33, and present or maintain closed joints between said rails and the post extensions even though the parts may otherwise fit loosely or inaccurately, or may have shrunk where formed of wood.

35 After the main or body part of the partition has been set up and fixed, as hereinbefore described, the post extensions 10, are moved up into the ceiling strip and are secured to the main posts by the screws and 40 brackets 11, as hereinbefore described.

45 The lower rails 15, are then slipped into place between the post extensions and rest on the top bars or rails 27, of the main partition. These rails 15, are not fastened or secured as the glass panes 13, will hold them in place. The upper crown moldings 16, which are provided in long lengths, can then be secured to the upper portions of the post extensions 10. The upper rails 14, can then 50 be slipped down between the post extensions and secured at proper points by screws passed thereto through the crown moldings 16. The upper rails are supported by the upper crown moldings and are not secured directly to the post extensions, when the structure is arranged according to my preferred embodiment. When the various 55 parts have been thus secured the glass panes 13, can be secured in the frames therefor 60 formed by parts 10, 14, 15.

65 The partition assembled and put up substantially as described can be readily taken down without marring or injuring the same, and as readily assembled and put up at some other point or location.

It is evident that various changes, variations, and modifications might be resorted to, that parts might be omitted, and other constructions added, without departing from the spirit and scope of my invention 70 and hence I do not wish to limit myself to the exact disclosure hereof but consider myself entitled to all such departures as fall within the spirit and scope of my invention.

What I claim is;—

75 1. A knock down partition comprising post units at their longitudinal vertical edges formed to receive and interlock with the vertical edges of filling section units, and individually complete filling section 80 units of approximately uniform height with the post units and at their upper ends having top rails of approximately the same transverse thickness as the upper ends of the post units, and crown molding adapted 85 to be removably secured to the side faces of the post units and said top rails and to be continuous across the joints between said section and post units.

90 2. A knock down partition or the like, comprising post units formed at their vertical edges to removably receive and interlock with filling section units, each post unit consisting of opposite side longitudinal pieces arranged a distance apart to afford 95 a space within the unit for an adjustable post extension, the longitudinal edges of said pieces being rabbeted to form longitudinal depressed shoulders, said pieces being secured together in fixed relation by stiff 100 flat metal fasteners arranged transversely between said pieces and at their ends fitting said shoulders and rigidly secured thereto.

105 3. A knock down partition or the like, comprising post units, each consisting of parallel longitudinal opposite side pieces spaced a distance apart and at their lower ends secured to a spacing block, the longitudinal edges of said pieces being rabbeted to form depressed seats with depressed 110 shoulders, and flat metal fasteners arranged transversely of said units and secured to and rigidly connecting said pieces, each fastener at both ends having spurs driven into said pieces, the ends of said fasteners 115 fitting said depressed shoulders.

120 4. A knock down partition or the like, comprising hollow post units formed at their vertical edges to removably receive and interlock with filling section units, each post unit consisting of opposite side longitudinal pieces arranged a distance apart to afford a space within the unit for an adjustable post extension, said pieces being secured together in fixed relation by stiff metal 125 fasteners arranged transversely between said pieces and at their ends fitting and rigidly secured thereto.

130 5. A partition comprising post units provided with upward extensions, section units

adapted to fill the spaces between the posts, said extensions having their longitudinal panel-edge-receiving edges formed with pairs of grooves, removable cross rails 5 adapted to extend between said extensions and to coöperate therewith, the end edges of said rails being grooved to removably receive and straddle said longitudinal edges of said extensions and having tongues to 10 removably enter said grooves, substantially as described.

6. A partition embodying vertically movable extension bars approximately throughout the lengths of their opposite longitudinal edges ribbed and rabbeted to receive the ends of panels and at the outer portions of said edges formed with longitudinal grooves, and removable bars forming the upper and lower rails to receive said panels, 15 said bars extending between said extension bars and having their end edges vertically grooved to straddle said ribbed and rabbeted edges of said extension bars and formed with parallel tongues to enter said grooves, 20 substantially as described.

7. A knock-down partition comprising post units, provided with longitudinally adjustable upward extensions, means to removably secure said extensions in the desired longitudinal adjustment, an upper crown molding connecting and traversing said extensions and removably secured thereto, and rail-forming bars removably fitting the edges of and extending between 25 said extensions and coöoperating therewith

in forming panel frames, the bars forming the lower rails of said frames removably resting on the main partition, and the bars forming the upper rails of said frames removably secured to and supported by said 40 molding.

8. A knock down partition consisting of removable post units adapted to be secured at their lower ends, bodily removable panel sections of approximately the same length 45 as said units and throughout their lengths removably interlocking therewith against lateral displacement, means for removably coupling the upper ends of the units and sections together against separation, said 50 post units provided with removable extensions arranged longitudinally thereof and projecting upwardly therefrom and approximately throughout the lengths of their 55 opposite edges formed to constitute the uprights of panel frames, removable cross bars extending between said extensions to form the upper and lower rails of removable filling panels above said sections and between said extensions, the opposite edges of said 60 several cross bars being similarly formed to transversely fit the edges of said extensions against lateral displacement without being supported by said extensions.

In testimony whereof I affix my signature in presence of two witnesses.

HENRY KLEIN.
